UNITED STATES PATENT OFFICE.

ALEXANDER W. KAUCHER, OF ROCHESTER, NEW YORK.

DESIGN FOR AN ILLUMINATED SIGN.

Application filed October 18, 1922. Serial No. 4,019. Term of patent 7 years.

To all whom it may concern:

Be it known that I, ALEXANDER W. KAUCHER, a citizen of the United States, residing at Rochester, in the county of Monroe and State of New York, have invented a new, original, and ornamental Design for Illuminated Sign, of which the following is a specification, reference being had to the accompanying drawing, forming part thereof.

I claim:

The ornamental design for an illuminated sign, as shown.

In testimony whereof I affix my signature.

ALEXANDER W. KAUCHER.
